UNITED STATES PATENT OFFICE.

DORSEY F. ASBURY, OF BROOMES ISLAND, MARYLAND.

RADIO APPARATUS.

Application filed December 1, 1925. Serial No. 72,514.

My invention relates to radio apparatus, particularly to receiving sets employing plural tuning units, and my object, generally speaking, is to provide means for operating the tuning units of a receiving set collectively and individually for the purposes set forth in my copending applications serially numbered 683,756; 687,080; 689,338 and 690,795.

More specifically my present purpose is to gain simplicity in construction and compactness in the arrangement of the parts of a plural tuning unit receiving set and to facilitate the tuning of such sets by disposing the tuning units in a novel relation to one another and providing a common operator therefor in the form of a single member effective when in one position to operate said units collectively and tiltable to different positions in which it is effective to operate said units individually.

It also is my present purpose to provide in connection with my tiltable operator, means whereby tendency to impart other than tilting movement to the same during tilting thereof is substantially eliminated; means to guide such operator during tilting thereof in the proper direction with respect to any individual part to be operated; means whereby said operator may be caused to operate the tuning units at different speeds with respect to one another; means whereby said operator may be held out of operative relation with all of the tuning units to permit operation of the latter by means other than said tiltable operator; and, should the tuning units ever be individually adjusted to such an extent as to destroy a substantially synchronized tuning relation between them, to provide means whereby said tuning units may quickly and easily be restored to a substantially synchronized tuning relation, so that when they are adjusted collectively, they will tune with any given wave length substantially simultaneously.

With the foregoing and other purposes in view, my invention consists in the novel features of construction, combination and arrangement of parts as will be hereinafter more fully described, illustrated in the accompanying drawings and defined in the appended claims.

In the drawings, wherein like characters of reference denote corresponding parts in the different views:—

Figure 1 is a front elevation of a plural tuning unit radio receiving set constructed in accordance with and including a preferred embodiment of my present invention;

Fig. 2, a section on the line 2—2 of Fig. 1; 60
Fig. 3, a detail section on the line 3—3 of Fig. 2;

Fig. 4, an end view of the slotted head of the operator supporting member;

Fig. 5, a view similar to Fig. 1 showing a 65 modified arrangement of tuning units and operator;

Fig. 6, a horizontal section on the line 6—6 of Fig. 5;

Fig. 7, a view similar to Fig. 6 showing 70 the operator tilted for operating an individual tuning unit;

Fig. 8, a view similar to Fig. 6 showing 75 the operator secured out of operative relation to all tuning units whereby the latter may be operated individually by means other than my operator;

Fig. 9, a section on the line 9—9 of Fig. 8;

Fig. 10, an end view of the slotted head 80 of the operator supporting member used with the two tuning unit receiving set shown in Figs. 5 to 9;

Fig. 11, a view similar to Fig. 5 showing 85 the operator of Figs. 5 to 9 associated with a three tuning unit receiving set;

Fig. 12, a view similar to Fig. 1 showing a further modification of my invention;

Fig. 13, a section on the line 13—13 of Fig. 12; and

Fig. 14, a detail view showing an arrangement of my invention in which a single tiltable operator may be made to collectively operate all three or only two units of a three tuning unit receiving set. 90

Referring to the drawings in detail, first 95 to Figs. 1 to 4, it will be observed that I have illustrated my invention as embodied in a radio receiving set including three tuning units 10, 11 and 12 in the form of variable plate condensers, each including, as usual 100 a stator *a* and a rotor *b*, said condensers being mounted upon one side of a panel 13 with the axes of their rotors *b*, preferably but not necessarily intersecting at a common point, whereby they are conveniently 105 disposed with respect to one another for operation by a single member, designated generally at 14, disposed on the reverse side of panel 13 from the tuning units.

Member 14 is in the form of a dial or 110

- wheel having a central bore within which is arranged a tube 15 having an outwardly directed lateral flange 16 at its outer end engaging a shoulder on the dial, and having
- 5 an inwardly directed lateral flange 17 at its inner end surrounding a sleeve 18 mounted on a stud 19 projecting outwardly from panel 13, said flange fitting around said sleeve more or less loosely, whereby said dial
- 10 is mounted in a permanent operative relation with respect to the tuning units 10, 11 and 12 for rotation, for movement bodily outwardly and inwardly with respect to panel 13, and for tilting movement, said
- 15 stud 19 being provided with an enlarged head 20 and said sleeve 18 being in contact at its inner flanged end with the panel 13, and at its outer end with said head, whereby a nut 21 threaded on the inner end of
- 20 stud 19, which latter extends through an opening 22 in the panel, may be tightened against a washer 23 disposed between it and the inner face of the panel to rigidly secure said stud to the panel.
- 25 Sleeve 18 is split longitudinally as best shown in Fig. 3, and within tube 15 is arranged a disk or washer 24, surrounding said sleeve and held against rotation by means of teeth 25 thereon operating within the channels formed by splitting said sleeve. Between said disk or washer and the head 20 of stud 19 is arranged an expansion coil spring 26, surrounding said sleeve and reacting from the head 20 against disk or
- 30 washer 24 and flange 17 to urge the dial or wheel 14 constantly towards the panel 13, whereby the inner face of said dial will be maintained normally in frictional driving contact with the edges of three disks 27, 28
- 35 and 29, mounted, respectively, on the shafts of the rotors *b* of the condensers 10, 11 and 12, said disks projecting through openings 30 in the panel into contact with the dial 14.

Formed in the outer end of the head 20

40 of stud 19 are three intersecting slots 31, 32, 33 extending, respectively, in the direction of the tuning units 10, 11 and 12, while threaded or otherwise secured in tube 15 and closing the outer end of the latter is a

45 plug 34 carrying centrally thereof upon its inner face a pin 35 extending normally into said slots at their point of intersection and adapted to travel in any one of them during tilting of the operator 14 to guide said

50 operator in the proper direction with respect to a selected individual tuning unit to be operated.

Projecting from the outer face of plug 34, centrally thereof, is a pin 36 of small diameter adapted to be engaged between the fingers of a person manipulating operator 14 (see Fig. 5) whereby tilting of said operator may be effected without tendency to impart other movements thereto, this being

55 of importance when it is desired to adjust

an individual tuning unit without disturbing previously effected correct adjustments of other units, said pin 36 providing a lever for facilitating tilting of operator 14, and, because of its small diameter, not being subjected, by engagement of a person's fingers therewith, to such tendency towards rotation as would effect movement of operator 14 to rotate the disks 27, 28 or 29 and destroy the adjustment of any tuning unit once correct adjustment thereof has been made.

Operator 14 normally is urged to the position shown in Figures 1 and 2 into frictional driving contact with the edges of 80 disks 27, 28 and 29 by spring 26, said operator reacting from each disk upon the others due to the angular relation of said operator with respect to said disks whereby it bears with substantially even force on each disk, 85 so that by rotating said operator said disks and their associated rotors *b* may be rotatably adjusted collectively. If, on the other hand, it is desired to adjust any rotor *b* individually, operator 14 is tilted (see Fig. 90 7) about its point of contact with the disk 27, 28 or 29, as the case may be, of the selected unit to be adjusted, out of contact with the disks of the remaining units, and then rotated to impart the desired amount 95 of individual adjustment to such selected unit. In this connection it will be observed that the bearing formed by flange 17 surrounding sleeve 18 normally is in a plane tangent to disks 27, 28 and 29 and is sufficiently loose whereby tilting of the operator about its point of contact with any individual disk is permitted without tendency of the operator to creep or slide on the disk upon which it is tilted. Also, it will be observed that the opening 22 in panel 13 through which stud 19 passes is sufficiently 100 large to permit stud 19 and consequently operator 14 to be adjusted towards or away from any particular condenser or condensers, 110 to cause the rotors *b* of the latter to be rotated at different rates of speed with respect to one another during rotation of said operator at a constant rate of speed.

The provision of disk or washer 24 between flange 17 and spring 26 overcomes any tendency of said spring to wind during rotation of operator 14 and thereafter to act torsionally to destroy adjustments of the rotors *b* made by means of said operator.

Disks 27, 28 and 29 are formed from any suitable pliable material whereby they may be bent (see Fig. 2) to dispose different peripheral portions thereof of a greater or less distance from the axis of operator 14 whereby rotation of said operator at a constant rate of speed will cause any one or more of rotors *b* to rotate at variable rates of speed, this for the purpose of causing each tuning unit to tune at substantially the same instant 130

with any given wave length when the units are moved collectively by operator 14 and assuming that the speed of rotation of one or more of the rotors *b* must be increased or diminished at predetermined times to maintain a substantially synchronized tuning relation between all of the units.

A stop device is associated with each rotor *b* to limit rotation thereof and said stop devices preferably are adjustable so that when each of the different tuning units is tuned correctly with a given wave length said stop devices may be secured in position to limit movement of the respective rotors *b* beyond their correctly tuned positions, the result being that if for any reason a substantially synchronized tuning relation between the different tuning units is destroyed, as, for example, if too great an amount of individual adjustment be imparted to any one or more units, a substantially synchronized tuning relation of the units may readily and easily be restored simply by rotating each of the rotors *b* until the respective stops become effective to limit further movement thereof, this being accomplished by rotating operator 14 until the stops of the different units successively become effective to limit further movement of the rotors *b*, operator 14 sliding with respect to the disks as they successively are halted by their stop devices, and when all disks have been halted, operator 14 then being lifted out of contact with the disks and rotated until the graduation thereon corresponding to the wave length with which the tuning units are tuned, is registered with a suitable pointer on the panel 13, when the apparatus is in readiness for correct collective adjustment of the tuning units by operator 14. Any preferred stop arrangement may be employed, the arrangement illustrated being of conventional form and for each unit consisting of a lug 37 on the disk associated with that unit and a screw 38 disposed in the path of movement of the lug and threaded in panel 13 whereby it may be adjusted to stop said disk at a desired point.

In Figures 5 to 10 I have shown an arrangement in which an operator 14' of substantially the same construction and having the same mode of operation as operator 14 is adapted for operating a pair of ordinary dials 41, 42 disposed on the same side of a panel 13' as operator 14' and attached to the rotors *b'* of a pair of variable plate condensers located to the opposite side of said panel. In this form of my invention operator 14' is provided with a band 43 of rubber or other suitable friction material engaging the dials 41, 42, and head 20' of stud 19' is provided with a single straight slot 44 in which the pin 35' is guided, this being all that is necessary since a two tuning unit ar-

rangement requires that the operator 14' be tilted only in a single direction. Pin 35' cooperates with slot 44 to support the outer portion of the operator against sagging, and as is manifest (see Figs. 8 and 9) the operator of both the preferred forms of my invention shown in Figs. 1 to 4 and of the modified form shown in Figs. 5 to 9, may be secured out of operative engagement with the parts it is intended to operate by pulling the same outward against the force of spring 26 or 26' as the case may be and then engaging pin 35 or 35' as the case may be against the outer face of head 20 or 20'.

Fig. 11 shows an obvious adaptation of the operator of Figs. 5 to 10 to a three tuning unit receiving set, the only change required over the construction of operator shown in Figs. 5 to 10 to effect such adaptation being an angular formation of the slots in the head of pin 19' as shown in Fig. 4.

In Figures 12, 13 and 14 I have shown a further modified construction having, however, the mode of operation characteristic of the constructions shown in the other forms of my invention. The tuning units 10^a, 11^a, 12^a are arranged as in Fig. 1, that is, with the axes of their rotors *b*^a preferably intersecting at a common point, rigid disks 27^a, 28^a and 29 being substituted for the corresponding pliable disks of the preferred construction. Upon the frames of the condensers 10^a, 11^a and 12^a is mounted a plate 50 and carried by this plate is a bearing for a shaft 51 on which is mounted a disk 52 normally engaging the peripheries of disks 27^a, 28^a and 29^a whereby collective adjustments are imparted to the rotors *b*^a when said shaft is rotated.

The aforementioned bearing for shaft 51 comprises a tubular member 53, shouldered exteriorly as at 54 and engaged through an opening in plate 50 with its shoulder abutting the inner face of said plate, a cap 55 being threaded on the end of said member that projects beyond the outer face of plate 50 whereby said member is closed at its outer end and held rigid with respect to said plate. In the inner end of member 53 is a reduced opening more or less loosely entered by the inner end of shaft 51, while contacting with the end face of said shaft within tubular member 53 is the cone point of a plunger 56, urged into contact with the end of said shaft by a compression coil spring 57 interposed between said plunger and cap 55, said shaft thus being urged outwardly and the disk 52 carried thereby being urged as a consequence normally into driving contact with the disks 27^a, 28^a and 29^a.

Shaft 51 extends through an opening in panel 13^a beyond the outer face of said panel where it is equipped with a suitable operating wheel 58 and with a pin 36^a as and for

the purposes set forth in connection with the previously described embodiments of my invention.

A plate 59 is secured to panel 13^a and in said plate are formed three radial slots 60, 61 and 62 alined, respectively, with the axes of the rotors b^a of the tuning units 10^a, 11^a and 12^a whereby shaft 51 is guided during tilting movement thereof to a position to operate any rotor individually. If desired, this plate may be arranged as shown in Fig. 14, so that when shaft 51 is tilted it will be engaged with the disks of two tuning units and disengaged from the disk of a single unit, whereby any pair of tuning units may be adjusted collectively.

The screws 63 that secure plate 50 to the frames of the condensers pass through enlarged openings 64 in said plate whereby the latter may be shifted thereby to shift the axis of shaft 51 and cause the rotors b^a to be rotated at different speeds with respect to one another during rotation of said shaft at a constant rate of speed.

In the construction illustrated in Figures 12 and 13, the bearing for shaft 51 is disposed in a plane tangent to disks 27^a, 28^a and 29^a whereby tilting of disk 52 is without tendency to slide on and effect the adjustment of the units.

As is apparent the disks of Figures 12 and 13 may be formed either of rigid or pliable material, and as is also manifest, said disks may be disposed entirely to the rear of panel 13^a whereby the necessity of slotting the panel may be avoided.

I claim:

1. In radio apparatus, a plurality of tuning units a part of each of which is movable, an operator having a contacting portion common to a plurality of said movable parts, said operator being rotatable to move said movable parts and being tiltable to different positions in which it is effective to move said movable parts individually, and means whereby said operator is supported for tilting movement about the point of contact of its contacting portion with the movable part of the tuning unit it is desired to adjust individually.

2. In radio apparatus, a plurality of tuning units a part of each of which is movable, an operator having a contacting portion common to a plurality of said movable parts, said operator being tiltable to different positions in which it is effective to move said movable parts individually, means constantly urging said operator in a direction to cause its contacting portion to contact with said movable parts, and means for

holding said operator with its contacting portion out of contact with all of said movable parts.

3. In radio apparatus, a plurality of tuning units a part of each of which is movable, a rotary operator located between and having a contacting portion common to a plurality of said movable parts, and means whereby the axis of rotation of said operator may be shifted with respect to said movable parts to cause said movable parts to be moved at different speeds with respect to one another during rotation of said operator at a constant rate of speed.

4. In radio apparatus, a tuning unit a part of which is movable, a rotary operator for moving said movable part, and a member of pliable material carried by said movable part and having peripheral contact with said operator for transmitting rotation of said operator to said movable part, said member being formed of pliable material whereby its peripheral portion may be bent into irregular form to cause said movable part to be rotated at variable angular velocities during rotation of said operator at a constant angular velocity.

5. In radio apparatus, the combination with a plurality of tuning units a part of each of which is individually movable, of an operator common to said movable parts effective to move them collectively; and a stop device associated with the movable part of each tuning unit for limiting movement thereof, said stop devices being adjustable whereby all of said tuning units may be stopped in correct tuning relation for any given wave length.

6. In radio apparatus, a plurality of adjustable tuning units, a rotatable operator normally in driving engagement with all of the units, and a mounting for said operator permitting its disengagement from all but one of the units solely by an axial tilting movement thereof.

7. In radio apparatus, a plurality of adjustable tuning units, a rotatable operator mounted for tilting movement into and out of driving engagement with said units, and a pin carried by and coaxial with said operator adapted to be engaged by the hand to impart tilting movements to said operator, said pin being of small diameter whereby tendency to rotate the operator during tilting movements thereof is substantially eliminated.

In testimony whereof I hereunto affix my signature.

DORSEY F. ASBURY.
